FIG. 1 is a front perspective view of an arm lounge seat showing our design in the form of a sofa;

FIG. 2 is a rear perspective view of the seat of FIG. 1 in the form of an arm chair;

FIG. 3 is a modified form of the seat of FIG. 1 but wherein the side panels have cut-out sections as shown; and

FIG. 4 is a rear perspective view of the seat of FIG. 1 in the form of an arm chair wherein the side panels have cut-out portions as shown.

The design is characterized by the plurality of fabric bands on the side panels in combination with the downwardly extending web panel at the rear thereof, all as shown.

We claim:

The ornamental design for an arm lounge seat or the like, substantially as shown and described.
